UNITED STATES PATENT OFFICE.

LOUIS ESCHNER, OF PHILADELPHIA, PENNSYLVANIA.

RECEPTACLE CLOSURE OR RETAINER.

No. 914,253.

Specification of Letters Patent.

Patented March 2, 1909.

Application filed April 23, 1908. Serial No. 428,816.

To all whom it may concern:

Be it known that I, LOUIS ESCHNER, a citizen of the United States, residing in Philadelphia, Pennsylvania, have invented certain 5 Improvements in Receptacle Closures or Retainers, of which the following is a specification.

My invention relates to means for retaining in place the closures of jars, bottles, cans, 10 boxes, or other receptacles, the globes of lamps, or other cylindrical bodies, (hereinafter, for convenience, termed "receptacles"), one object of my invention being to render such means cheap, simple, convenient 15 to operate, and effective for their intended purpose, and a further object being to adapt the invention for use in connection with bottles or other receptacles which are already provided with closures such as caps, stoppers, corks or the like. The first of these 20 objects I accomplish by providing on the outer portion of the receptacle adjacent to the mouth of the same, a series of convex horizontal cams with rounded or cam-like ends, 25 which cams are adapted to engage with a corresponding set of elastic, concave horizontal cams with cam-like ends formed on the inner side of a ring which constitutes the retainer hereinafter referred to. The second object of 30 my invention I attain by so constructing said ring member that it may engage with a cap, stopper, cork, or other form of closure with which a bottle or other receptacle is already provided, and, in some cases, by also providing a separate cam ring for application to 35 the receptacle, when the latter itself is not equipped with cams, on the outer portion of the rim.

In the accompanying drawings Figure 1 is 40 a perspective view of the neck portion of a bottle or jar constructed in accordance with my invention; Fig. 2 is an inverted perspective view of a cap or closure for use in connection with said jar; Fig. 3 is a sectional view 45 of the upper portion of the jar and its cap, said section being taken through cam portions of the cap which are in engagement with cams on the jar; Fig. 4 is a similar sectional view, but with the section taken 50 through portions of the cap which are not in engagement with cams on the jar; Fig. 5 is a perspective view of part of a bottle and a ground glass stopper therefor, and of the various members of a retainer for use in connection with said stopper; Fig. 6 is a per-

spective view showing, in operative relation with one another, the parts represented in Fig. 5; Fig. 7 is a vertical sectional view of the same, and Fig. 8 is a perspective view of a special embodiment of my invention, and 60 Fig. 9 is a sectional view of the same on a larger scale.

Referring first to Figs. 1, 2, 3 and 4 of the drawings, 1 represents the upper portion of a bottle, jar, or other receptacle having, externally disposed thereon, a series of horizontal cams 2, these cams being, by preference, equidistant from one another and separated by spaces 3, each slightly longer than one of the cams on the retainer hereinafter referred 70 to. The cams and the intervening spaces are externally curved or convex in transverse section, as shown in Figs. 3 and 4, and the cams are also rounded or of cam-like form at one or both ends 4, the latter construction 75 being illustrated in Fig. 1, and being preferred in order that the ring member may be applied by movement either to the right or left. Below the cams the receptacle has a continuous annular rib 5 which is, by preference, provided with a recess 6, as shown in Fig. 1. The ring member of the retainer which co-operates with the aforesaid cam formation on the receptacle may either form 80 a tight, and, if necessary, a hermetically 85 sealed closure, or, if it does not constitute part of a cap, it may serve to confine to the mouth of the receptacle a packing disk, a cork, a glass cup or stopper or other form of closure which seals said receptacle either 90 hermetically or not, as desired. The cap may carry a brush, may constitute a dispensing nozzle, or may be constructed in many 95 other known ways depending upon the use for which the receptacle is intended, the special construction of the cap forming no part of my invention.

As shown in Figs. 2, 3, and 4, the ring element 7 of the retainer forms part of a cap 9, and has formed in it inwardly projecting 100 horizontal cams 10 equaling in number and dimensions the cam formations 2 on the receptacle, the inner face of each of these cams being concave to correspond with the convex cross section of the corresponding 105 cam 2, and being rounded or cam-like at each end to facilitate its engagement with said cam 2. The cams 10 do not extend to the lower edge of the ring 7, said lower portion of the ring overlapping and forming a 110

neat joint with the annular rib or flange 5 of the receptacle, and said lower portion of the ring having one or more lugs 11 for engagement with the recess or recesses 6 in 5 the rib 5, such engagement serving to indicate to the user when the cams 10 of the ring are in proper engagement with the cams 2 on the receptacle. By preference, the cap 9 has a depending annular rib 12 which 10 bears upon the sealing disk 13 or other closure at a point above the bearing or seat of the same upon the mouth of the receptacle and serves to firmly press this portion of 15 said closure upon said bearing or seat, and thereby effect a secure, and, if necessary, a hermetically tight sealing of the receptacle.

In applying the ring member 7, the same is held so that its cams 10 are in register within the spaces 3 between the cams 2 and 20 the ring is then passed downwardly until its rib 12 contacts with the sealing disk or other closure upon the top of the jar. The ring is then turned in one direction or the other so as to bring the forward, cam-like 25 portions of the cams 10 into contact with the cam-like ends of their corresponding cams 2, the latter therefore exerting pressure upon the cams 10 and forcing the same downwardly and outwardly until they are 30 finally seated beneath the cams 2, as shown in Fig. 3, this downward and outward pressure then continuing so as to retain the rib 12 of the cap 9 firmly in contact with the sealing disk or other closure and insure the 35 pressure of the latter firmly upon the bearing or seat at the top of the receptacle. When the ring 7 is in place, its lower portion contacts with the outer portion of the rib 5, and thus provides a neat finish and 40 prevents access of dust or other foreign matter to the sealing ring or disk 13. The engagement of the lug 11 on the ring with the recess 6 in the rib 5, besides indicating when the cams 10 are in proper engagement 45 or register with the cams 2, also serves to prevent ready displacement of the ring and thus lessens the risk of its release from the control of said cams. Preferably the recess 6 is formed in a slight swell or enlargement 50 on the rib 5, whereby the lug-carrying portion of the ring member 7 is slightly expanded as the lug approaches the recess, and the lug is thus caused to snap into the recess, and is retained by the resiliency of the ring member. The relation of the lug and recess may 55 be reversed, without affecting their functions, hence in the claims I have alluded to these members as offsets. The curvature of the outer faces of the spaces 3 between the ribs 2 serves, by engagement with the cams 10 of the ring 7 when the same are 60 passed downwardly through said spaces, to temporarily retain the cap in loosely fitting relation to the receptacle and permit escape of steam or vapor from the latter 65

when its contents are being heated for sterilizing purposes before the final sealing of the receptacle. By pressing up the cams 10 from the ring 7 the elasticity of the entire ring is available to maintain said cams in engagement with the cams 2 of the receptacle, and by forming the cams above the bottom edge of the ring said cams are rendered less yielding than inwardly curved fingers on the lower edge of the ring would be, thus 75 insuring a firmer retention of the ring when its cams are in engagement with those of the receptacle.

In that embodiment of my invention shown in Figs. 5, 6 and 7, ^{1a} represents a bottle or other receptacle having a ground glass stopper ^{13a}, the bottle being unprovided with a cam formation around the top but having the usual projecting rib or flange 14 around the mouth. In order to adapt 85 my invention for use in connection with such a receptacle, I apply to said rib 14 an external split ring 15, having cams ^{2a} formed thereon, and having also a shoulder 16 and downwardly projecting tongues 17. The shoulder 90 16 engages with the underside of the rib 14 and serves to confine the ring 15 vertically to the bottle, and the tongues 17 can be held by the fingers of one hand while the ring member of the retainer is being manipulated by 95 the fingers of the other hand to cause its cams to engage with those of the ring 15. The ring member ^{7a} has an opening of greater diameter than the closing portion of the stopper ^{13a} so that said ring member can 100 be applied to the stopper from below, and a split ring 19 is also applied to the stopper, said split ring overlapping the shoulder of the stopper and underlapping the flange of the ring member ^{7a}, as shown in Fig. 7, whereby 105 it provides not only a means whereby the ring member ^{7a} can exert pressure upon the stopper, but also a means for preventing the said ring member ^{7a} from being detached from the stopper when the latter is removed 110 from the bottle. This method of confining the ring member to the stopper may be adopted whether the cams 2 are formed on the receptacle itself or on a split ring applied thereto. When it is desired to employ a 115 lower rib in connection with the ring having the cams ^{2a}, a split ring ^{5a} may be properly disposed, and held in position by engagement with offset or recessed portions of the tongues 17, as shown in Figs. 8 and 9, said tongues 17 constituting enlargements on the ring and having the notches ^{6a} for the reception of the lugs ^{11a} on the ring member of the closure. 120

Both forms of closure or closure-retaining device which I have shown and described are 125 cheap, they provide for the convenient application or removal of the ring member by a partial turn of the same, and they insure the effective retention of a sealing disk or ring in contact with its seat upon the mouth of the re- 130

ceptacle, or the secure confinement of a cap, stopper, cork, or other closing device with which the receptacle may be provided.

I claim:

5. 1. The combination of a receptacle having thereon externally disposed and longitudinally separated horizontal cams, convex in cross section and having cam-like ends, and a ring member having internally disposed and longitudinally separated elastic horizontal cams, concave in cross section and having cam-like ends, said concave cams engaging with the convex cams on the receptacle.
15. 2. The combination of a receptacle having thereon externally disposed and longitudinally separated horizontal cams, convex in cross section and having cam-like ends, and below said cams a horizontal rib with offset thereon, with a ring member having internally disposed and longitudinally separated elastic horizontal cams, concave in cross section and having cam-like ends said concave cams engaging with the convex cams on the receptacle, and said ring member also having an offset portion for engaging that of the rib on the receptacle to retain the ring member from rotary movement in either direction.
3. The combination of a shouldered stopper or other closure with a ring member having a flanged opening through which a portion of the closure can pass, and a split ring engaging said closure and interposed between said flange on the ring member and the portion of the closure which can pass through the opening within said flange.
4. The combination of a receptacle having

cams thereon, a shouldered stopper or other closure, a ring member having a flanged opening through which a portion of the closure can pass, and a split ring engaging said closure and interposed between said flange of the ring member and the portion of the closure which can pass through the opening within said flange, said ring member being provided with cams for engaging the cams on the receptacle to which the closure is adapted.

5. The combination of a receptacle having thereon externally disposed convex cams separated from one another by spaces which likewise have convex outer faces, and a ring member, having internally disposed and longitudinally separated elastic concave cams, which are adapted to engage with the rounded undersides of the convex cams on the receptacle and also with the convex faces of the spaces between said cams.

6. The combination of a receptacle having a flange around the mouth, a split ring engaging said flange and having cams thereon, a shouldered stopper or other closure for the receptacle, a split ring applied to said closure, and a ring member engaging said second split ring and having cams for engagement with those of the split ring on the receptacle.

In testimony whereof, I have signed my name to this specification, in the presence of two subscribing witnesses.

LOUIS ESCHNER.
